METHOD OF PHOTOGRAPHING PRINTING FORMS

George L. Morrison, Evanston, Ill.

Application December 2, 1948, Serial No. 63,037

5 Claims. (Cl. 95—5)

1

The present invention relates broadly to the art of printing, and is particularly concerned with apparatus and methods for photographing printing surfaces of either the raised or the intaglio type. In certain of its aspects, the present invention is related to, and is an improvement upon, the invention of my prior application, S. N. 20,214, which was filed on April 10, 1948.

As pointed out in my said prior application, it is the practice in the everyday production of certain types of gravure and other photo-mechanical printing surfaces, as for example in the photo-gravure and rotogravure processes, to effect the transfer to that surface of text, and other material to be reproduced, by a process which requires the utilization of a photographically produced print or transparency of such text or other material. Prior to the invention disclosed in my said prior application, it has been the practice in obtaining a print or transparency for this purpose to set up a printing form containing type and/or type-slugs, and the various other plano-relief surfaces to be reproduced, this form being then inked, and an impression on paper made therefrom. Finally, the inked impression has been photographed, and the resulting print or transparency used in the production of the gravure or other photo-mechanical printing surface.

Despite the loss of clarity which results from the inking and printing operations, this process has been extensively used for the reason that the direct photographing of printing forms has been considered impractical, if not in fact impossible. In my prior application, I have disclosed a method of preparing printing forms (which may include type and type-slugs of various kinds and varieties as well as printing plates made of various metals) so as to obtain, by a direct photographic process, a photographic negative or positive which can be used in the production of gravure and other photomechanical printing surfaces of any of the known types.

In the practice of the invention disclosed in my said prior application, the surfaces of the printing form are treated in such manner that the plano-relief areas to be photographed have generally uniform light reflectance properties and are sharply outlined by relatively non-reflecting areas. This makes possible the direct photographing of printing forms, as above described.

The principal object of the present invention is to provide an improved apparatus and procedure for illuminating and for photographing printing forms and like copy material and more particularly, to provide an improved apparatus and procedure for illuminating and for photographing the plano-relief surfaces of letter-press printing forms so as to create a shadow area which outlines and sharply defines such surfaces from their background. Other objects include the provision of a novel method and apparatus for photographing raised or intaglio printing surfaces, in accordance with the above-stated principal object, by the use of conventional photographic

5 10 15 20 25 30 35 40 45 50 55 60

2

methods and materials to produce prints or transparencies having adequate density and contrast for photo-mechanical purposes, without the need for local or general intensification of the image; and generally, the provision of improved apparatus and methods for obtaining photographic prints or transparencies of the various plano-relief, printing surfaces usually contained in printing forms.

The invention is based on the discovery that high density, sharply defined, photographic images of uniform contrast can be obtained from type and like printing surfaces by the use of an ordinary photo-engraver's camera, provided that the illumination of the surface to be photographed is effected in such manner that a shadow area is created around each of the plano-relief surfaces to be photographed and provided further that the photographic image is produced by light which is to some extent diffusely reflected from that surface. The obtaining of photographic images by this procedure requires the use of specially designed, although not unreasonably complicated, light sources and may also involve certain preliminary treatment of the surfaces to be photographed, as will hereinafter appear.

Certain illustrative types of illuminating apparatus and photographic equipment particularly designed for practicing the process of the present invention are illustrated in the accompanying drawings, wherein:

Figure 1 is a perspective view of a photo-engraving camera, copy board, and light source suitable for use in photographing printing forms and the like in accordance with the invention;

Figure 2 is an enlarged, side elevational view, partially in section, of the apparatus illustrated in Figure 1;

Figures 3 and 4 are, respectively, end and plan elevations illustrating the manner in which type characters or other plano-relief surfaces are illuminated during the practice of the method of the present invention;

Figure 5 is a front elevational view of the light-source comprising a part of the apparatus illustrated more completely in Figures 1 and 2;

Figure 6 is a view showing another type light-source which may be used in practicing the invention; and

Figure 7 is a diagrammatic view illustrating a further modified light-source and camera arrangement in accordance with the invention.

The photographic apparatus illustrated in Figures 1 and 2 includes a camera 11, a copy board 13, and a source of illumination 15. The camera 11 may be a conventional photo-engraver's camera and is desirably of the dropped-bed type, as illustrated. The camera 11 is mounted upon springs 17 or other vibration dampening means, and it is equipped with a lens 19 of the usual type, which may include a conventional shutter and an iris diaphragm. The lens 19 is supported upon the forward bellows-support 21, and that support is

desirably movable toward and away from the rear bellows-support 23 in order to permit focusing of the camera in conventional manner. The rear bellows-support 23 includes a ground-glass plate for focusing, as indicated at 25, and may also be provided with means for receiving a plate holder, or with other equipment for positioning sensitized material in the plane of the ground-glass during the photographing operation. The copy board 13 is supported at the forward end of the camera bed, and the plane of the copy board 13 is located symmetrical with, and at right angles to, the optical axis of the lens 19, which is indicated by the dot and dash line 27.

The illuminating means or light-source 15 for the printing surface, printing form, or other material to be photographed is of special design. In order to accomplish the objective of a shadow area surrounding each of the plano-relief surfaces to be photographed, the light-source must be of such dimensions, and so positioned, that light, in the form of an image of at least a portion of the light-source, will be reflected from all parts of a plane surface coincident with the surface to be photographed to, or approximately to, the optical center of a lens symmetrically positioned in front of that surface. This means that an ideal light-source, as above described, should produce illumination equivalent to the illumination produced by a solid sheet of light having overall dimensions which are (for full size photographic reproduction) twice the corresponding dimensions of the surface to be photographed, the sheet of light being located in a plane which is parallel to the surface to be photographed and which intersects the optical axis of the lens at, or approximately at, the optical center thereof, and the intensity of the sheet of light being such that uniform density images are produced from all of the reflecting areas.

It can be shown that in order to obtain exactly uniform density photographic images when using a light-source as above described, the intensity of the illumination provided by the light-source should vary at different points in the plane of the surface being photographed as the reciprocal of the fourth power of the cosine of the angle that each such point makes with the optical axis of the camera lens. For relatively small lens angles, illumination at an intensity level corresponding to the inverse square law (i. e. even intensity illumination over the entire surface being photographed) will approximate this requirement. However, when the lens angle becomes much greater than about 10 degrees, increased intensity illumination in the outer regions of the surface being photographed in accordance with the reciprocal of the fourth power of the cosine, as above described, will be found highly desirable. The criticality of the increase in illumination required in the outer regions of the light-source depends to some extent upon the latitude of the photographic materials employed, as might be expected.

The above-stated requirements of an ideal light-source are not wholly attainable in practice. Of necessity, there must be an opening in the center of the light-source for the lens. Also, a solid sheet of light of sufficient dimensions for the illumination of the relatively large surfaces included in a printing form or the like, is not obtainable. Thus, the light-sources actually available for use in the commercial practice of the invention can constitute only approximate equivalents of the solid-sheet light-source, as above

described. Close approximations are, however, possible. For example, for the illumination of relatively small area surfaces, where inverse-square law illumination is adequate, a reciprocating bank of fluorescent lamps, as illustrated in Figure 6 can be used as the light-source. Unfortunately, the intensity of fluorescent lamps is comparatively low, and the resultant longer exposure is not considered good practice. Another, and more satisfactory, very close equivalent is a revolving bank of individual lamps, as illustrated at 15 in the drawings. This arrangement is particularly suitable for photographing complete printing forms and similar large areas, in that it provides an easy and inexpensive means for obtaining readily controlled variation in the intensity level of the illumination over the area being photographed, and, in addition, the intensity of the individual lamps can be varied to match the desired exposure time.

It should be noted that both of the above-suggested light-sources provide relative movement of the source of illumination and the material being photographed during the photographing operation. This is an important feature in obtaining even illumination of printing forms and other material of substantial area with an absence of spot reflections, when using practical equivalents of the ideal light-source described in the foregoing.

The dot and dash lines 29 in Figure 2 represent the path of a ray of light from the outer edge of the illuminating means shown in Figures 1 and 2 to the outer edge of a plane reflecting surface disposed on the copyboard 13, and from that surface to the optical center of the lens 19. Figures 3 and 4, wherein the lines 30 indicate the path of incident and reflected light rays, illustrate the manner in which illumination of this type produces the desired shadow area outlining the various plano surfaces contained in the type form or other material disposed on the copyboard. From an examination of Figure 3, it will be evident that almost no light will be reflected to the lens from surfaces which are not at least nearly parallel to the plane of the copyboard. It will be evident, therefore, that the light-source will produce the desired shadow area about the type, type-slugs or the other printing surfaces usually contained in a printing form. As is well-known, all of such surfaces are conventionally outlined by rather steep-sided, plane or curved surfaces. The small area adjacent the optical axis of the lens which is not illuminated in exact accord with the foregoing, does not cause any difficulty, apparently because ordinary variations in the surfaces to be photographed produce a self-compensating effect.

The obtaining of illumination which will provide the outlining shadow areas and which will reflect light from the plano surfaces, as described, requires the use of a light-source which is of substantially greater area than the area of the printing surface, printing form, or other material to be photographed, although, as will be apparent from the geometry of Figure 2, the area of the light-source may vary, depending upon the distance between the source of illumination and the material being photographed. The essential feature is that the relative dimensions and position of the light-source shall be such that the illumination produced on the surface to be photographed is equivalent to the illumination produced, during ordinary full size photography, by a solid sheet of light of proper intensity having

overall dimensions which are twice the corresponding dimensions of the surface to be photographed, when that sheet of light is positioned in a plane which is parallel to the surface to be photographed and which intersects the optical axis of the lens, at, or approximately at, the optical center thereof. Under the stated condition of ordinary, full size photography, the sheet of light and the lens are, of course, spaced from the surface to be photographed a distance equal to twice the focal length of the lens. 10

The most satisfactory position for the light-source is the above described position adjacent the camera lens, but as above noted, other arrangements are possible, provided that the equivalent illumination is produced. For a given focal length lens, it can be shown that if the light-source is located nearer the surface to be photographed, the overall dimensions and area may be decreased; and if it is located farther away, they must be increased. However, when the light-source is located in any position other than adjacent the camera lens, it becomes difficult to accomplish proper illumination of the material to be photographed, due to interference with the camera or with the lens. It is also not essential that the light-source be disposed in a plane (i. e. that the light-source be flat) although the plane construction is greatly to be preferred, both from the viewpoint of obtaining better control of the illumination, and from the viewpoint of simplifying the construction and operation of the apparatus. In view of the advantages of using a light-source which is substantially planar and which is located adjacent the lens, the light-source illustrated at 15 in Figure 2 is of the planar type and is shown in this position.

In the particular apparatus illustrated in Figures 1 and 2, the light-source 15 includes a rotatable light-support 31, which may constitute a circular disc of plywood, or equivalent structure, having mounted thereon a plurality of ordinary, incandescent filament, light bulbs 33, as illustrated. The light-support 31, is attached to a flange 35 (Figure 2) which constitutes a part of a cylindrical hub 37, and the hub 37 is adapted to be disposed upon a hollow bearing member 39, so as to permit rotation of the light-source. The bearing member 39 is illustrated as being attached to the forward bellows-support element 21 of the camera, but it may desirably be attached to a separate support to eliminate vibration. The light-support 31 and the hub 37 are retained in position on the bearing member 39 by a suitable retainer ring 41 and the arrangement is such that the entire structure is freely rotatable on the bearing member 39. Electrical power is conducted to the light bulbs 33 by means of a pair of slip rings 43, mounted on the forward bellows-support 21, and a brush structure 45 which is carried by the rotatable light-source itself.

As previously noted, it is intended that the light-source 15 shall be rotated during the normal operation of the apparatus, and this is accomplished in the illustrated structure by means of a combination-motor and speed control unit 47, which is operatively connected to the rotatable light-support 31 by a V-belt 49 and pulley 51. The edge of the light-support disc is grooved to receive the V-belt. The individual light bulbs 33, which desirably are of the same wattage and light output, are so arranged on the disc support 31, that a substantially increased amount of illumination is provided in a direction outwardly from the optical axis of the camera lens.

More specifically, the individual light bulbs 33 are positioned at spaced intervals along a spiral (merely as a convenient means of mechanical arrangement), this spiral being indicated by the dot and dash line 55 in Figure 5. The exact position of each light unit 33 is, however, in accordance with a predetermined radial relationship to the optical axis. This position is determined by first fixing the radial distances of the inside and outside lamps (in accordance with the maximum size of the copy to be reproduced) and then locating the additional lamps between these two limits on such radial spacing that the radial distances between the light units decrease toward the outside limit to provide an increasing light intensity in accordance with the cosine fourth-power-law requirements. It can be shown that this arrangement of lights in a moving light-source, when the light units used are of substantially equal light-output, and are positioned in a generally flat plane, will effect the illumination of copy which is centrally disposed with reference to the light-source, in a plane extending generally parallel thereto, so as to produce a photographic image of substantially even intensity throughout the entire area thereof.

The arrangement and spacing of the lamps can also be determined empirically, as for example, by placing a first surface mirror on the copy board, then placing a single lamp at differing radial distances on the lamp support, and actually measuring the intensity of the illumination obtained for each lamp position. Additional lamps can then be arranged on the lamp support so as to increase the illumination on the copy board in the exact ratio necessary to obtain even tone images during the photographing operation.

The rotating light-source 15, in effect, scans the printing surface, printing form, or other copy to be photographed, so as to produce the desired shadow area outlining the various individual plano-relief surfaces contained therein, and by virtue of the controlled variation in the intensity of the illumination, it overcomes the difficulties experienced with prior art illuminating means, and particularly, the difficulties resulting from uneven density in the photographic images. The motion of the individual light units 33 also prevents localized, high intensity reflections, which might impair the quality of the image in the photographic plate or transparency.

When the apparatus illustrated in Figures 1 and 2 is used for photographing a printing surface, printing form, or the like, the material to be photographed is positioned on the copy board so as to be centrally located with respect to the optical axis 27 of the camera lens. The light-source 15 is then placed in operation, and after focusing of the camera 11, if necessary, an exposure is made in conventional manner. Normally, the print or transparency will be the same size as the material to be photographed, which will result in the copy being located at a distance from the optical center of the lens 19, which is approximately twice the focal length of that lens. The ground glass 25, during focusing, and the sensitized material during the exposure, will be located the same distance at the rear of the optical center of the lens.

When conventional photographic materials are used, and ordinary development and fixing procedures are followed, the intensity of the illumination provided by the light-source is desirably such that exposures of the order of about one-half to one minute will be required. In a par-

ticularly satisfactory embodiment of the apparatus, wherein standard 100 watt bulbs were used in the rotating light-source 15, and the exposure time was within the range of about 40 to 60 seconds, the supporting disc 31 for the individual light bulbs 33 was rotated at a speed within the range of from about 25 to 30 R. P. M. This light-source had an effective diameter of about 36 inches, the lens 19 having a focal length of 18 inches, and it was found possible to accomplish satisfactory illumination of material which could be contained within a circle approximately 18 inches in diameter. Under these conditions, light reflected from substantially all points in a plane surface disposed in the plane of the printing surface or other material to be photographed, and parallel to that surface, will intersect the optical axis of the lens at, or forwardly of, the optical center of that lens. Also, the individual plane surfaces are outlined by a shadow area, and the desired illumination is thus effected.

It will be understood, as previously noted, that it is possible to use light-sources of other types, and it is also possible to use other optical arrangements during the photographing operation. For example, in Figure 6, there is shown a generally flat, light-source 59, which comprises a plurality of fluorescent-tube units 61, symmetrically disposed on a plane support 63. At the central portion of the light-source 59, an elongated opening 65 is provided for the camera lens 19 with which the source of illumination is used, and it is intended that the light-source 59 shall be oscillated back and forth during the photographic operation to prevent localized reflections. Generally, if the amount of movement of the light-source is equal to the distance between the center lines of the adjacent fluorescent tubes 61, satisfactory results will be obtained.

When a flat light-source, such as is illustrated at 59 is used in connection with photographic apparatus similar to that illustrated in Figures 1 and 2, the light-source is desirably positioned in a plane which is adjacent the camera lens, and which is parallel to the surface to be photographed. To obtain the desired illumination in such a set-up, the maximum dimensions and the area of the material to be photographed should not be greater than one-half the maximum dimensions and the area of the light-source, as indicated by the dotted outline 67 in Figure 6, and the material to be photographed should be located on the copyboard in a central position with respect to the optical axis of the lens. The intensity of the illumination produced on the material to be photographed by the light-source 59 is not as great as in the previously described embodiment, although quite satisfactory results can be obtained with a light-source of this character, particularly when the material to be reproduced is in the form of ordinary type or type slugs. The illumination produced by a light-source of this character is substantially in accordance with the inverse square law, and hence, is most suitable for use in photographing relatively small areas.

It is also possible to arrange the optical system in a right angle set-up, as illustrated in Figure 7. In this arrangement, the material to be copied, which is indicated at 69 and which may be a printing surface, or a combination of such surfaces as in a printing form, is positioned in a horizontal plane. Above the copy there is provided a transparent mirror 71 which is disposed at an angle of 45° to the plane of the material to be photographed. A suitable source of illu-

mination, indicated generally at 13, which can be similar to the light-source shown in Figure 1 or Figure 6, is disposed above the mirror 71 and the material to be photographed, and the surface of that material is illuminated by light which passes through the transparent mirror. Here again, the dimensions of the light-source are such that a plane surface disposed in the plane of the printing surface or other material to be reproduced, and parallel to that surface will reflect light into the mirror 71 at such angles that it will intersect the optical axis of the system at, or forwardly of, the optical center of the lens. The lens is indicated diagrammatically at 15 and the photographic plate or other sensitized material at 77. The right angle arrangement shown in Figure 7 produces a lateral reversal of the image, as compared with the image produced by a straight-line arrangement, such as illustrated in Figures 1 and 2, and this may be desirable for certain types of photo-mechanical reproduction. The practice of the method illustrated in Figure 7 is limited by the size of the transparent mirror 71 and by the cost of creating optically-plane surfaces in that mirror. For small units, as for example in the photographing of a single line of type or a single type-slug, the arrangement is very satisfactory. Also, such an arrangement could be used to advantage in photographing lines of type-patrices presented to it by a type-setting machine, similar to a linotype. In the arrangement of Figure 7, the camera and lighting unit can be interchanged in position, as is done in a microscope. This is quite satisfactory for small areas, but is somewhat inefficient for large areas, probably due to the scattering of light on both sides of the mirror.

In the interest of using as small a light-source as possible, the maximum dimensions of that source need be no greater than is necessary to cause light reflected from a plane surface disposed at the edge of, and parallel to, the material to be photographed to intersect the optical axis of the lens at the optical center of that lens. Preferably, the light-source is flat, as in the illustrated embodiments, and is disposed in a plane which is parallel to the surface of the material which is to be photographed. The light-source may be positioned at various points along the optical axis of the system, but as previously explained, it is most desirably positioned adjacent the lens. It will also be understood that the light-source need not be planar, although from a constructional viewpoint, this arrangement is greatly to be preferred.

In addition to the provision of a light-source which creates a shadow area outlining the individual plane-relief printing surfaces to be photographed, the accomplishment of all of the advantages of the method of the present invention requires that the surfaces to be photographed shall be abraded so as to produce a non-directional, uniform, matte surface thereon, prior to the photographing operation. Also, in order to accomplish all of the advantages of the invention, it will usually be found necessary to treat the background surfaces of the copy material so as to suppress light reflection from those surfaces. Light-sources, as above described, provide an outlining shadow area around the individual printing surfaces, but because the background surfaces are normally curved or of varying angular relation with reference to the plane of the light source (and may be parallel to that plane, in certain regions, as illustrated for ex-

ample at 79 in Figures 3 and 4) light will be reflected from these regions into the lens, unless such reflection is suppressed.

Reflection from the background surfaces can be conveniently suppressed by applying a light-absorbing coating to those surfaces, as for example, in accordance with the procedure set forth in my prior application, S. N. 20,214. As therein described, the coating may comprise a mixture of water, liquid soap, and a light-absorbing pigment, which is sprayed onto the entire area of the surface to be photographed and is subsequently removed from the printing surfaces only by the use of a cloth-covered block or felt or equivalent means. Other coatings, such as optical lacquer and the like, may also be used, but a water soluble coating is preferred because it is very easy to remove after use.

The abrading of the surface to produce a uniform matte finish may also be accomplished in accordance with the general procedure set forth in my prior application S. N. 20,214. As described in that application, very satisfactory results can be obtained when the abrading is accomplished by the use of a block of rubber or rubber-like compound containing fine abrasive material, similar to the metal polishing blocks in common use in the jewelry and metal-polishing industries. In the practice of the method of the present invention, however, it is quite important that the matte surface shall be non-directional in nature. In other words, the lines should be produced by rubbing the block or other abrasion-carrying material, over the surface in a plurality of different directions. Also, the individual lines produced by the abrasion operation should be sufficiently small to be incapable of resolution in the optical system of the camera. In ordinary, full-scale photographic reproduction processes, this means that the individual lines should not have a greater width than about one thousandth of an inch, and preferably should not have a greater width than about one ten-thousandth of an inch.

When the material to be photographed contains etched copper or zinc plates, which frequently have the original photo-resist still in place thereon, the abrasion is best accomplished by the use of fine, abrasive dust, such as very fine pumice, flower of emery, diatomaceous earth, or similar abrasive material, which will remove the resist as well as abrade the printing surfaces. Abrasive materials of this type are conveniently applied to the surface of the plate by means of a moistened pad of cotton or cloth. A fine grade of kitchen cleaner can sometimes be used for this purpose. Since these materials are frequently light in color, the abrasion of resist-bearing copper and zinc plates is most advantageously accomplished prior to the application of the background coating of light absorbing material. Here again, the application should be non-directional in character.

The surface resulting from the abrasion procedure described above has a substantially uniform, non-directional, matte finish, which acts to reflect a high percentage of incident light in accordance with the cosine law, but which, at the same time, produces sufficient diffusion of the reflected light to produce what is generally designated in the illumination art as "spread reflection." This tends to even out irregularities in the reflecting surface and produces a much more satisfactory photographic image than is possible under conditions where true specular re-

flection occurs. The abrasion of the printing surfaces, as above described, does not in any way impair the printing characteristics of surfaces on which it is used, or otherwise prevent the subsequent use of such surfaces in ordinary printing operations.

Upon the completion of the abrasion operation and the coating of the background areas intermediate the plano-relief surfaces to be photographed with a suitable light absorbing coating, the printing form or other copy material to be reproduced is ready for photographing. Because of the arrangement of the light-source which produces a shadow area completely outlining each of the individual surfaces to be reproduced, particularly sharp photographic images of those surfaces can be obtained, even when the printing form or other copy contains printing surfaces made of differing metals. In instances where surfaces of differing metals are to be photographed simultaneously, it is particularly important that the abrasion of the surfaces to be photographed shall be non-directional in nature and that all background surfaces extending between the shadow area produced by the light-source shall be treated to suppress light reflection therefrom; it is also quite important that the light-source shall move relative to the surface being photographed during the photographing operation.

30 This eliminates spot reflections, and to a large extent, compensates for any inequalities in the light output of the component parts of the light-source.

One of the most important advantages of the present invention results from the fact that a printing form can be photographed without requiring a make-ready operation, make-ready being the operation followed in evening the height of the various elements in a printing form. The usual printing forms always include at least some elements which are of different height than the other elements in the form, and these must be leveled in ordinary printing in order to obtain a satisfactory ink print. Due to the high intensity of illumination which is made possible by the present invention, it is possible, without unduly increasing the exposure time, to stop-down the lens sufficiently to provide a depth of field which will include all of the constituent elements of the printing form, despite variation in the height of those elements.

The practicing of the invention, when using conventional photographic material, results in a positive image which can be produced on sensitized paper for pasting up with other copy and re-photographing, or a positive film can be made for use directly on a press plate. Contact negatives can be made from the film positive, or the film positive can be reversed chemically, depending on the process to be followed. Also, lateral reversal of the image can be obtained by the use of straight-line image-reversers, a mirror behind the lens, or the recently developed direct reversing films which can be exposed from either side, or by using thin-base film and then turning it over. Strip film turned over can also be used in obtaining a reversed image, or a contact negative made from the positive can be reversed chemically to yield a reverse reading positive.

Other variations and arrangements in the use of the apparatus and procedure of the invention will suggest themselves to those skilled in the art. The most important advantage of the invention results from the ability of the apparatus and procedure to make possible the direct photo-

tographing of printing forms and copy material containing spaced-apart, plano-relief printing surfaces of small area, by the use of conventional photographic materials and procedures, so as to obtain a high contrast, uniform density print or transparency which can be used in the photo-mechanical art. Various of the features of the invention believed to be new are expressly set forth in the appended claims.

I claim:

1. The method of photographing printing forms and like copy material containing spaced-apart, plano-relief printing surfaces, which comprises treating the background of said copy material to suppress light reflections from the non-printing areas of said copy material, abrading said printing surface to produce thereon a uniform, non-directional, matte finish, illuminating said copy material by a planar light source which has over-all dimensions that are at least twice the corresponding dimensions of the copy material to be photographed, which is located adjacent the lens in a plane that is normal to the optical axis of the lens and which is of increasing intensity in a direction outwardly from the optical axis of the lens such that the light intensity at any point on the surface of the copy material to be photographed varies substantially in accordance with the reciprocal of the fourth power of the cosine of the angle which such point makes with the optical axis of the lens, and then photographing said copy material.

2. The method of photographing printing forms and like copy material containing spaced-apart, plano-relief printing surfaces and a light absorbing background, which comprises abrading said printing surfaces to produce thereon a uniform, non-directional, matte finish wherein the maximum width of the abrasion lines is within the range of from about .001 to .0001 inch, illuminating said copy material by a planar light source which has over-all dimensions that are at least twice the corresponding dimensions of the copy material to be photographed, which is located adjacent the lens in a plane that is normal to the optical axis of the lens and which is of increasing intensity in a direction outwardly from the said optical axis such that the light intensity at any point on the surface of the copy material to be photographed varies in accordance with the reciprocal of the fourth power of the cosine of the angle which such point makes at the optical axis of the lens, and then photographing said copy material.

3. The method of photographing a printing element containing metallic relief printing surfaces, which comprises applying a light-absorbing coating to the entire surface of said element, removing said coating from said relief printing surfaces while leaving the coating intact on the background portions of said printing element, abrasively treating said printing surface to produce thereon a clean, matte finish of such fineness that the individual lines in said surface are not visible to the naked eye, illuminating said printing element by a generally planar light source which has over-all dimensions that are at least twice the corresponding dimension of the material being photographed, which is located adjacent the lens in a plane that is substantially normal to the optical axis of the lens and which is of increasing intensity in a direction outwardly from the optical axis of the lens such that the

light intensity at any point on the surface of the copy material to be photographed varies substantially in accordance with the reciprocal of the fourth power of the cosine of the angle which such point makes with the optical axis of the lens, and then photographing said printing element.

4. The method of photographing printing forms and like copy material containing spaced-apart, plano-relief printing surfaces which comprises abrading said printing surfaces to produce a uniform, non-directional matte finish thereon, treating the background of said copy material to suppress light reflections from the non-printing areas of said copy material, illuminating the material to be photographed by a planar light source which has overall dimensions that are at least twice the corresponding dimensions of the copy material to be photographed, which is located adjacent the lens in a plane that is normal to the optical axis of the lens and which is of increasing intensity in a direction outwardly from the optical axis such that the light intensity at any point in the surface of the copy material to be photographed varies in accordance with the reciprocal of the fourth power of the cosine of the angle which such point makes with the optical axis of the lens, and then photographing said copy material.

5. The method of photographing printing forms and like copy material containing spaced-apart, plano-relief printing surfaces and a light absorbing background, which comprises abrading said printing surfaces to produce thereon a uniform, non-directional matte finish, illuminating the material to be photographed by the use of a generally planar light source which is centered about the lens of the camera in a plane substantially normal to the optical axis of the lens, said light source having over-all dimensions which are at least twice the corresponding dimensions of the copy material to be photographed, and said light source being of increasing intensity in a direction outwardly from the optical axis of the lens, such that the intensity of the illumination at different points on the surface of the copy material varies approximately as the reciprocal of the fourth power of the cosine of the angle that each such point makes at the optical axis of the lens, and then photographing said copy material.

GEORGE L. MORRISON.
